United States Patent Office

Des. 217,993
Patented July 7, 1970

217,993

COMBINED CALENDAR AND PENHOLDER

Cecil B. Woofter, Newton, Iowa, assignor to
The Vernon Company

Filed Sept. 5, 1969, Ser. No. 19,037

Term of patent 14 years

Int. Cl. D19—03

U.S. Cl. D74—5

FIG. 1 is a perspective view of a combined calendar and penholder embodying my new design;

FIG. 2 is a front elevational view of the combined calendar and penholder thereof;

FIG. 3 is a back elevational view of the combined calendar and penholder thereof;

FIG. 4 is a side elevational view of the combined calendar and penholder; and

FIG. 5 is a top plan view of the combined calendar and penholder.

I claim:

The ornamental design for a combined calendar and penholder, substantially as shown.
